PRESSER FOOT FOR SEWING MACHINES

Fritz Ebert, Oberndorf-on-the-Neckar, Germany

Application January 23, 1935, Serial No. 3,169
In Germany February 1, 1934

5 Claims. (Cl. 112—235)

The present invention relates to sewing machines adapted to simultaneously produce two different sewing operations, i. e. to make a joining seam and a cover seam at the same time in a single operation. If the joining seam is finished, simultaneously the cover seam also is produced. A presser foot suitable for such machines must, therefore, be capable of working for each of these operations. Thus, in order to obtain a perfect suture, the presser foot must be able to adapt itself as far as possible to double cross seams. This adaptability requires an extensive subdivision and ability of movement respectively of the presser foot.

15 The main object of the invention is to provide a presser foot which is subdivided several times in its longitudinal direction as well as in its lateral direction and in which each of these movable parts is adjustably arranged and individually limited in its downward movement, the pressure of each of these parts being resiliently adjustable.

The presser foot part adapted to cooperate with the joining seam consists of four portions which 25 may be moved independently of each other. With regard to cross seams, occurring sometimes at the left and sometimes at the right hand side, the front portion is subdivided in its longitudinal direction. The second portion of the 30 presser foot, provided in case of a sewing machine having staggered needles with the stitch hole for the needle producing the joining seams, is also subdivided in its longitudinal direction for reasons mentioned already above. Besides the four 35 pivotally arranged parts, resilient side portions are provided in the main body.

To allow a more or less large piercing of the folded part of the one piece of fabric, a stop extending beneath the under surface of the presser 40 foot is adjustably fixed to one of the parts of the subdivided presser foot.

This stop which is of the greatest importance for carrying out sewing operations on machines adapted to feed off the arm forms an obstacle for 45 the fabric during withdrawing of the latter, because on the upward movement of the presser foot this stop, on account of being carried by a spring actuated portion of the presser foot, is pressed against the throat plate, whereby the 50 fabric sewn or joined together is caught by this stop.

In one construction according to the invention this drawback is obviated by the fact, that the portion of the presser foot carrying the stop for 55 adjusting the folded portion may, during lifting

of the presser foot, be lifted independently or shifted against the action of its spring.

With presser feet for sewing machines having a guide edge, it has already been known to move the guide edge by means of a handle beyond the under surface of the presser foot as soon as it is not required for use, thus simultaneously obtaining the advantage that, with the presser foot lifted, the guide edge does not form an obstacle on withdrawing the fabric.

With regard to this known cutting out of the edge guide, the subject matter of the invention has the advantage that the edge guide, during lifting of the presser foot, is automatically swung upwardly, thereby saving one operation.

In the accompanying drawings, forming part of the specification, two embodiments of a presser foot according to the invention are shown by way of example.

In these drawings:

Fig. 1 is a plan view of a presser foot according to the invention,

Fig. 2 shows a side elevation, partly in section on the line 2—2 of Fig. 1,

Fig. 3 is a rear elevation,

Fig. 4 is a front elevation,

Fig. 5 shows a section on the line 5—5 of Fig. 1,

Fig. 6 is a side elevation, partly in section on the line 6—6 of Fig. 1, illustrating the fabric with a cross seam passing from one side to the other,

Fig. 7 shows a side elevation corresponding to Fig. 2 with the parts in another operative position,

Fig. 8 is a section on the line 8—8 of Fig. 1,

Figures 9 and 10 are side elevations of a modified form of the invention showing the parts of the presser foot in two different positions, and

Fig. 11 shows a section on the line 11—11 of Fig. 9.

The front portion of the presser foot consists of the parts 1 and 2 which are pivotally arranged on two different screws 3 and 4 provided for this purpose with bearing surfaces. The second portion of the presser foot having the stitch hole 5 for the needle producing the joining seam, consists of the parts 6 and 7, which also are pivotally arranged on screws 8 and 9 also provided for this purpose with bearing surfaces.

The two pivots formed by the screws 8 and 9 are arranged as low as possible in order to obtain a uniform lifting of the parts 6 and 7.

Each of these four movable parts 1, 2, 6 and 7 is provided with a second lever arm 10, 11, 12 and 13 respectively. These lever arms serve as

bearings for springs 19, 20, 21 and 22 mounted in the main body 14 of the presser foot. The pressure of these springs may be regulated by adjusting the screws 15, 16, 17 and 18. The parts 1, 2, 6 and 7 are, therefore, not only individually movable, but the pressure of each of the single parts upon the work piece is also individually adjustable. Furthermore, a special device is provided for each single part to control the amount of its downward movement. This device for the parts 1 and 2 consists of rail 23 mounted in the main body 14 in which two screws 24 and 25 are adjustably arranged which bear against the lever arms 10 and 11 of the parts 1 and 2. Each of the parts 6 and 7 is provided with a third lever arm 26 and 27 respectively, each carrying an adjustable screw 28 and 29 respectively bearing against the main body 14, whereby the swinging movement of the parts 6 and 7 in a downward direction is limited.

The main body 14 proper of the presser foot has a bore 30 in which the presser foot rod 41 is inserted and is provided with the stitch holes 31 and 32 for the needles producing the cover seam. The main body 14 is further, in well known manner, provided with two resiliently movable side portions 33 and 34. The spring 35 for these side portions 33 and 34 is connected to the main body 14 by means of a screw 36 and bears against pins 37 and 38 arranged in the movable portions 33, 34. The downward movement of these portions 33, 34 is limited by a pin 39 (Figures 2, 6 and 8) which is mounted in the main body 14 and extends with its ends into holes 40 which are provided in the said side portions 33 and 34 and are of considerably greater diameter than the cross section of the pin 39.

Furthermore, the movable part 2 is provided with a recess 42 adapted to receive a stop 44 the position of which may be adjusted and fixed by means of a screw 43.

The stop 44 serves for adjusting the folded portion of the left hand web of the fabric. According to the position of the stop 44, the needle 45 passing through the stitch hole 5 pierces the folded left hand web 54 of fabric in a greater or shorter distance from the fold 55. Thus, as seen from Fig. 11, the stop 44 has been shifted as far as possible towards the part 1 of the presser foot, 50 so that the needle pierces the web 54 of the fabric as near the fold 55 as possible.

As shown in Fig. 6, the parts 1 and 2 have been lifted by the cross seam, whereas according to Fig. 7 the work piece and the cross seam respectively have been fed and have lifted the parts 6 and 7, while the parts 1 and 2 rest again on the single thickness of the fabric. As shown in Fig. 8, the pivoted parts 1 and 6 and the resilient side portion 33, not shown in these figures, 60 rest upon a single thickness of the fabric.

This construction of the presser foot is, of course, also adapted for sewing machines in which the stitch holes for all three needles are arranged in a single plane or in alignment. Under certain circumstances one pair of the movable parts may then be omitted.

The presser foot according to the invention may also be employed for all kinds of sewing machines, and it is not intended to limit the invention to a presser foot suitable for a sewing machine having an overhanging arm and which is adapted for horizontally feeding the fabric in a direction towards the overhanging arm, as, without departing from the spirit of the invention, the presser foot may also be used in con-

nexion with a sewing machine of the kind having an overhanging arm and which is adapted for horizontally feeding the fabric in a direction away from the overhanging arm, i. e., from the cylinder. In machines of this latter construction, the finished work automatically drops off the cylinder, i. e., the work falls from the cylinder of the machine as soon as the sewing operation is finished.

The device for lifting the stop 44 on withdrawing of the joined fabric is shown in Figures 9 to 11.

The lever arm 11 of the part 2 of the subdivided presser foot, pivotally arranged on the screw 4 and pressed against the fabric by means of the spring 20, projects somewhat beyond the main body 14 of the presser foot and has an inclined surface 45. Connected to the fixed frame of the sewing machine, by means of screws or the like, is a stop 46 the free end of which is directed towards the presser foot and formed as an inclined surface 47 corresponding to the inclined surface 45. A lever 48 is pivoted to the frame of the machine by means of bolt 49 or the like. A ring 50 connected to the presser foot rod 41 by a screw 51 carries a pin 52, and a recess 53, provided in the lever 48, is adapted to cooperate with the pin 52.

In operation, a pressure exerted on the lever 48 or a pressure exerted on the pedal adjusting the presser foot causes lifting of the latter, whereby the inclined surface 45 at the end of the lever arm 11 is brought in contact with the inclined surface 47 of the stop 46, so that the part 2 of the presser foot is swung against the action of the spring 20, i. e. is lifted from the fabric. As soon as the recess 53 of the lever 48 engages the pin 52, the rod 41 is arrested in its elevated position and therefore the stop 44 is held in a position out of the path of the fabric. The stop is prevented from moving against the throat plate of the sewing machine, and therefore cannot form an obstacle for the work piece when the latter is withdrawn from the machine. The two pieces of fabric to be sewn together are fed into the machine under a certain angle and the left hand piece 54 of fabric is bent off in an acute angle, so that the bent edge 55 runs along the stop 44 (Fig. 11). The latter is adjustably arranged, so that the position of the bent edge 55 also may be altered, with the result that the material may be pierced at a desired distance from the edge 55. This stop 44 would impede the removal of the fabric from the cylinder, i. e., the fabric would be caught by the stop. To obviate this disadvantage, the construction of the machine is such, that on lifting of the presser foot an additional swinging movement is imparted to the movable portion of the presser foot together with the stop, whereby the stop 44 is moved out of the range of the fabric which may then easily be stripped off.

What I claim is:

1. A presser foot for sewing machines comprising a main body, three pairs of foot members arranged with their operating parts in a single horizontal plane one behind the other, pivotally arranged levers extending upwardly, one for each of the foot members of the pair arranged furthest from said main body and of the middle pair, each of said levers forming part of its corresponding foot member, springs mounted in said main body, one for cooperation with each of said levers, set screws screwed into said main body, one for cooperation with each of said springs,

5 a rail provided at said main body, set screws provided in said rail cooperating with said levers forming part of said foot members of the pair arranged furthest from said main body and limiting the downward movement of said last mentioned pair of foot members, a rearwardly extending lever forming part of each foot member of said middle pair and a set screw in the end of each of said rearwardly extending levers co-operating with said main body and limiting the downward movement of the foot members of said middle pair.

10 2. A presser foot as set forth in claim 1 in which two side portions forming the third pair 15 of foot members are yieldingly arranged in said main body and a spring is provided between said main body and said foot members of the middle pair the ends of which bear against said side portions.

20 3. A presser foot as set forth in claim 1 in which an adjustable stop adapted to be fixed in position by a screw is arranged in a recess provided in one of said foot members of said

pair extending furthest from said main body.

4. A presser foot as set forth in claim 1 in which an adjustable stop adapted to be fixed in position by a screw is arranged in a recess provided in one of said foot members of said pair extending furthest from said main body and means are provided by which, on lifting of the presser foot, said foot member carrying said stop is automatically lifted against the action of its spring. 5

10 5. A presser foot as set forth in claim 1 in which an adjustable stop adapted to be fixed in position by a screw is arranged in a recess provided in one of said foot members of said pair extending furthest from said main body and in 15 which said upwardly extending lever forming part of said foot member carrying said adjustable stop is prolonged beyond said main body and provided at its free end with an inclined surface cooperating with another inclined surface provided at a stationary stop fixed to the machine frame. 20

FRITZ EBERT.
